(57) **CLAIM**

The ornamental design for lighting fixture, as shown and described.

DESCRIPTION

FIG. 1 is a perspective view of the lighting fixture of the present disclosure;

FIG. 2 is a bottom view thereof;

FIG. 3 is a front view thereof; the back view being the same;

FIG. 4 is a right side view of thereof; the left side view being the same; and,

FIG. 5 is a top view of thereof.

Those portions of the present invention which are presented in phantom illustrate the environment of the design only and form no part of the claimed design. Moreover, the shading presented in the accompanying drawings is provided merely to highlight the contour of the invention and is not intended to be illustrative of texture or gloss.
